US00D421819S

United States Patent [19]

Heeter et al.

[11] Patent Number: Des. 421,819[45] Date of Patent: * Mar. 21, 2000[54] LIPSTICK CASE

[75] Inventors: Kristina B. Heeter, Grand Rapids, Mich.; Thierry Francois DeBaschmakoff, Paris, France

[73] Assignee: Amway Corporation, Ada, Mich.

[] Term: 14 Years

[21] Appl. No.: 29/110,506

[22] Filed: Sep. 8, 1999

[51] LOC (6) Cl. 28-03

[52] U.S. Cl. D28/85

[58] Field of Search D28/76-90; D9/503, D9/504, 516, 575, 338, 529; 132/317, 318, 320; 401/61-98; 206/385
